UNITED STATES PATENT OFFICE.

OSCAR C. ROOS, OF ALLSTON, MASSACHUSETTS.

RADIOTELEGRAPH TRANSMITTING SYSTEM.

Specification of Letters Patent. Patented July 15, 1919.

1,369,778.

Application filed July 14, 1917. Serial No. 180,527.

To all whom it may concern:

Be it known that I, OSCAR C. ROOS, a citizen of the United States, and a resident of Allston, in the county of Suffolk and State of Massachusetts, have invented a new and useful Improvement in Radiotelegraph Transmitting Systems, of which the following is a specification.

My invention relates to radio-telegraph transmitting systems and more especially to systems which are energized by substantially continuous oscillations such as those developed by an oscillating-arc circuit.

In systems of this type the oscillations developed in the antenna are generally not simple harmonic but consist of a fundamental and various multiples thereof, the higher of which if reinforced by antenna resonance are generally of considerable amplitude.

The existence of these higher harmonics imposes a limitation to efficient selective transmission and it is therefore the main object of my invention to provide means for absorbing the higher harmonics so that the transmitted electromagnetic waves will be substantially simple harmonic. A further object of my invention is to provide means for rectifying such higher harmonics and for utilizing the energy of the resulting unidirectional impulses to assist the main current in feeding the arc.

Two illustrative embodiments of my invention are shown conventionally in the accompanying drawings but it will be understood that various modifications may be made both in the apparatus and the system of circuits without departing from the principle of my invention.

In the drawings—

Figure 1 is a diagram of a radio-telegraph transmitting system involving my invention; and Fig. 2 is a diagram of the modification.

A transmitting antenna T is associated in any suitable manner with the oscillating-arc circuit containing the condenser C and electrodes A, said antenna being shown in the present instance as serially connected to said circuit through the primary of the transformer M and as grounded at E.

Inductively associated with the antenna system which is attuned to a predetermined fundamental frequency, said frequency being determined by the antenna itself and its associated circuit or circuits, is a circuit M, C', M', C'', L' attuned to the frequency of

one of the multiples of said fundamental frequency, said circuit being shown in Fig. 1 as including the secondary of the transformer M, the primary of the transformer M', the condenser C', and a parallel-branch circuit, one branch of which contains the condenser C' or an equivalent capacity, and the other the inductance L' or an equivalent inductance. The parallel-branch circuit is so attuned as to have a maximum impedance at the fundamental of said antenna system,—for example said circuit may be attuned to the frequency of the fundamental of the antenna system, so that for currents of said fundamental frequency the circuit M, C', M', C'', L' will have a practically infinite impedance.

As shown in Fig. 2 the anti-resonant circuit C'', L'' may be omitted if the circuit M, C', M' is made highly selective.

The harmonics developed in the antenna system by an oscillating-arc circuit which do the greatest damage are the higher harmonics from the fifth to the thirteenth, but it will be understood however that my invention is not limited to use with an antenna system energized by an oscillating-arc circuit and that it may be employed wherever desired to absorb one or more harmonics irrespective of the manner in which the oscillations are created. It will also be understood that two or more absorbing circuits may be used to eliminate two or more harmonics and that where an oscillating-arc circuit is used to energize the antenna, two or more such absorbing circuits are preferable, as indicated in Fig. 2, in which the circuit M₁, C₁, M₁' represents a second absorbing circuit.

The energy of the higher harmonic oscillations absorbed from the antenna system may be utilized for assisting the main current in feeding the arc and to this end I may use any suitable means capable of rectifying such oscillations. For this purpose I prefer the well known rectifying arrangement V which serves to rectify both pulses of the oscillations translated from the absorbing circuit to the secondary of the transformer M', and the resulting unidirectional current is impressed upon the arc by conductors which include the choke coils I', I'', and the regulator R. Where two or more absorbing circuits are used, the rectifiers are all connected to said conductors, as indicated in Fig. 2 in which V₁ is a rectifier con-

nected to the secondary of the transformer M' .

As shown in the present instance the arc circuit is energized by the direct current generator G which is connected thereto through choke coils I, I . While for illustrative purposes I have shown my invention as applied to a radio-telegraph system, it will, of course, be understood that it may be used with advantage in any other type of electromagnetic wave radiating system.

As indicated the transformer M, M' may be designed for variable spatial separation of the primary and secondary windings. It will be apparent that the absorbing circuit or circuits may be coupled to the antenna system in any of the usual ways in which resonant circuits are associated with antenna system.

Various arrangements have been proposed for insuring the simple harmonic vibration of the antenna of a coupled system in which the oscillations are created by the periodic disruptive discharge of a condenser across a spark gap; but so far as I am aware it is broadly new with me to so arrange matters that the electromagnetic waves transmitted from an antenna system energized by an oscillating-arc circuit are simple harmonic in form. By the term "oscillating-arc circuit" as used herein I desire to be understood as meaning a circuit which includes a condenser and arc-electrodes or other device or devices so arranged that when said circuit is energized by direct current substantially continuous oscillations are produced.

Having described illustrative embodiments of my invention without however limiting the same thereto, what I claim and desire to secure by Letters Patent is:

1. A radio-telegraph transmitting system, comprising in combination an antenna system, means for creating electrical oscillations therein, a circuit associated with the antenna and attuned to one of the harmonics of the fundamental thereof, and a parallel-branch circuit, one branch of which includes a capacity and the other an inductance, serially connected with said circuit, said parallel-branch circuit being attuned to the fundamental of said antenna system.

2. A radio-telegraph transmitting system, comprising in combination an antenna system, means for creating electrical oscillations therein, a circuit associated with the antenna and attuned to one of the harmonics of the fundamental thereof, and a parallel-branch circuit, one branch of which includes a capacity and the other an inductance, serially connected with said circuit; said parallel branch circuit being so attuned as to have a maximum impedance at the fundamental of said antenna system.

3. A radio-telegraph transmitting system, comprising in combination an antenna sys-

tem, means for creating electrical oscillations therein, a circuit associated with the antenna and attuned to one of the harmonics of the fundamental thereof, and a parallel-branch circuit, one branch of which acts as an equivalent capacity and the other as an equivalent inductance, serially connected with said circuit, said parallel branch circuit being so attuned as to have a maximum impedance at the fundamental of said antenna system.

4. A radio-telegraph transmitting system, comprising in combination an antenna system having a definite fundamental frequency, an oscillating-arc circuit arranged for creating therein electrical oscillations of said frequency, a circuit associated with the antenna and attuned to one of the multiples of said frequency, and a parallel-branch circuit, one branch of which includes a capacity and the other an inductance, serially connected with the last mentioned circuit, said parallel-branch circuit being attuned to the fundamental of said antenna system.

5. A radio-telegraph transmitting system, comprising in combination an antenna system having a definite fundamental frequency, an oscillating-arc circuit arranged for creating therein electrical oscillations of said frequency, a circuit associated with the antenna and attuned to one of the multiples of said frequency, and a parallel-branch circuit, one branch of which includes a capacity and the other an inductance, serially connected with the last mentioned circuit, said parallel-branch circuit being attuned so as to have a maximum impedance at the fundamental of the said antenna system.

6. A radio-telegraph transmitting system, comprising in combination an antenna system having a definite fundamental frequency, an oscillating-arc circuit arranged for creating therein electrical oscillations of said frequency, a circuit associated with the antenna and attuned to one of the multiples of said frequency, and a parallel-branch circuit, one branch of which acts as an equivalent capacity and the other as an equivalent inductance, serially connected with the last mentioned circuit, said parallel-branch circuit being attuned so as to have a maximum impedance at the fundamental of the said antenna system.

7. A radio-telegraph transmitting system, comprising in combination an antenna system, an oscillating-arc circuit arranged for creating electrical oscillations therein, a circuit associated with the antenna and attuned to one of the harmonics of the fundamental thereof, means associated with the last mentioned circuit for rectifying the oscillations absorbed therein and means for impressing the resulting unidirectional current on the arc circuit.

8. A radio-telegraph transmitting system, comprising in combination an antenna sys-

tem, an oscillating-arc circuit arranged for creating electrical oscillations therein, a circuit associated with the antenna and attuned so as to have a maximum impedance at the frequency of the fundamental of said antenna system and a minimum impedance at the frequency of one of the harmonics of said fundamental, means associated with the last mentioned circuit for rectifying the oscillations absorbed therein and means for impressing the resulting unidirectional current on the arc circuit.

9. A radio-telegraph transmitting system, comprising in combination an antenna system, an oscillating-arc circuit arranged for creating electrical oscillations therein, a circuit associated with the antenna and attuned to one of the harmonics of the fundamental thereof, means associated with the last mentioned circuit for rectifying both the positive and the negative pulses of the oscillations absorbed therein and means for impressing the resulting unidirectional current on the arc circuit.

pressing the resulting unidirectional current on the arc circuit.

10. A radio-telegraph transmitting system, comprising in combination an antenna system, an oscillating-arc circuit arranged for creating electrical oscillations therein, a circuit associated with the antenna and attuned so as to have a maximum impedance at the frequency of the fundamental of said antenna system and a minimum impedance at the frequency of one of the harmonics of said fundamental, means associated with the last mentioned circuit for rectifying both the positive and the negative pulses of the oscillations absorbed therein and means for impressing the resulting unidirectional current on the arc circuit.

In testimony whereof, I have hereunto subscribed my name this 2nd day of July, 1917.

OSCAR C. ROOS.
